CHECKROW WIRE FOR PLANTERS

Arnold E. W. Johnson, Chicago, Ill., assignor to
International Harvester Company, a corpora-
tion of New Jersey

Application July 7, 1934; Serial No. 734,143

8 Claims. (Cl. 24—114.5)

This invention relates to a check wire for planters. More particularly, it relates to an improved check wire formed as a continuous length of wire with the buttons rigidly secured in spaced relation 5 thereon.

In check row planters, a check wire is used, on which buttons are formed at regular spaced intervals for tripping a mechanism which deposits the seed in a hill. In multiple row planters, a rock-shaft extends across the planter to operate a plurality of seed dispensing mechanisms whereby a plurality of hills are deposited in transverse alignment. The wire is stretched across the field and is maintained by careful restaking at alternate ends in as nearly the same longitudinal position as possible, whereby the buttons check the successive passages of the planter with the hills in transverse alignment.

In all check wire now in use individual lengths 20 of wire are utilized with the ends secured together to form a tripping knot. In a wire formed in this manner it is necessary to use a low carbon wire in order to form the necessary knots or fastening means for securing the lengths of wire to previously formed knots. Such wire, when wound around spools used in storing the wire, obtains a more or less permanent set, which has the effect of plurality of leaf springs secured together end to end when stretched across the field. In addition to the spring tension of this nature there is 25 springing in the loops where the lengths of wire are secured to the knots. As a result of these conditions, and due to the use of a low carbon wire, which stretches when excess tension is applied, great difficulty has been encountered in maintaining the proper tension to prevent longitudinal movement of the wire with subsequent inaccurate checking. To overcome this difficulty, a substantially stretchless check wire having integral radial upsets at the buttons has been 30 designed as disclosed and claimed in assignee's co-pending application Serial No. 640,426, filed October 31, 1932, of which this application is a continuation in part.

45 The principal object of the present invention is to provide a continuous or single length check wire with which a novel form of hardened steel elements are utilized to obtain large and long wearing contact means or buttons for engaging the planter check fork.

This object is attained by the construction as shown in the drawing, in which:

50 Figure 1 is an elevational view of a planter check head showing a check wire in operative position in engagement with the check fork;

Figure 2 is an enlarged elevational view of a short length of wire incorporating the present invention;

55 Figure 3 is a diagrammatic cross sectional view 60 illustrating a pair of dies serving as electrodes to

form opposite shoulders or upsets on a wire, illustrating the method by which applicant's improved check wire button is formed; and

Figure 4 shows the same elements as Figure 3 with the dies in closed position, whereby the disk portion of the button is embedded in the metal of the check wire.

A check row planter head has been illustrated in Figure 1 to illustrate the use of a check wire and the desirability of providing a large hardened check button for operating the planter mechanism. The check head 10 of the planter is rigidly mounted on transverse bars 11, which form a part of the planter frame structure. Vertical rotating guide spools 12 and horizontal guide spools 13 provide means for guiding the check wire through the check head. A rockshaft 14, mounted for oscillation on the check head carries an upstanding bracket 15 on which the check fork 16 is mounted. Said check fork is of the conventional construction, being formed as two spaced elements diverging intermediate their ends to provide for release of the check button after the rockshaft 14 has been rotated into the position shown in Figure 1. These parts of the planter mechanism have not been shown in detail as the desirability of check buttons having substantial size and formed of durable material is well known. As a further development in the check wire claimed in the application above referred to, the peripheral portions of the buttons for the check wire of this invention are formed as separate elements 18 particularly formed to best accomplish the check fork operating function and to utilize a minimum of material. These elements also are shaped to facilitate formation of the button.

As shown in the sections of Figures 3 and 4, the peripheral portions of the buttons are preferably formed by employing disk elements 18 formed with torus or doughnut shaped peripheral portions 19 and flat, thin, center portions or webs 20. As will be noted, the peripheral portions of the check buttons are of a substantial thickness and are rounded to provide an engaging surface for contacting the check fork 16. The elements constituting the periphery of the buttons are formed by a die operation from sheet metal. They may be formed of any material and may be heat treated for hardening, to increase durability. The flat, thin center portions 20, which are in the nature of webs, are formed centrally thereof with openings 21 sufficiently large to permit their being threaded on a smooth, continuous length of wire 22.

Said wire is of a high carbon content and is substantially non-stretchable for the maximum tension used in planting operations. It is, however, of an analysis which will permit upsetting operations following the application of electric

heat through electrode dies 23. Said dies are formed in halves to grip the wire, and are clamped a short distance away from a button which has been threaded on the wire. Current is then supplied sufficient to heat the length of wire between the dies to a working temperature. The dies are then brought together to the position shown in Figure 4, whereby portions of the wire at opposite sides of the button are upset to form shoulders abutting the flat, thin, central portion of the disks, substantially filling the recesses formed by this thinner central portion and engaging the inner side of the torus shaped periphery. Sufficient metal is upset at each side of the button to substantially fill the recesses, whereby the upset portions lie within planes tangent to the outer surfaces of the peripheral portions of the disk portion of the buttons. With this construction the upset portions do not engage the check fork, the rounded peripheral portions, which may be hardened as above pointed out, forming the contacting surfaces for engaging the check forks.

For use as a check wire in a check row planter a continuous, one-piece wire has marked advantages. In the first place, it does not stretch to any appreciable extent, as a high carbon wire may be used and as there are no loops in which a spring action is obtained. This is a very important feature and one of the outstanding results accomplished by the check wire of this invention. As previously pointed out, the spring action and the stretch, which are always obtained in check wires of the prior art, present a problem which has been solved only by the skill of the operator and by spring measuring appliances at the securing posts used to hold the ends of the wire. Although a wire of this type is constructed of a high carbon steel, it does not have the same tendency to kink and act as a spring in that respect as a wire composed of individual sections loosely connected together. When a continuous piece of wire is laid out, the kinking or bending action, which has become a permanent set of the wire, due to winding it on a drum, does not have the same action as the short free links of a sectional wire. A high carbon, one-piece wire may be laid in a straight line across a field with the application of a comparatively low tension. As an additional advantage the application of excess tension does not stretch the wire even temporarily, and for that reason it is not necessary to accurately apply the same tension to the wire at all times to maintain it in substantially the same position and to prevent longitudinal travel across the field.

The additional advantages of utilizing a continuous wire with large check buttons having wear resistant engaging surfaces have been pointed out in connection with the description. It is possible in a wire of this nature to chose any material and size for the check buttons which gives the most satisfactory operation.

It is to be understood that applicant has shown and described only a certain preferred construction of his improved check wire and that he claims all modifications falling within the scope of the appended claims.

What is claimed is:

1. A check wire for planters comprising a continuous length of wire provided with spaced check buttons including apertured disks having rounded peripheral portions and thin apertured central portions, said disks being rigidly located in posi-

tion on the wire by radially upset portions of the wire, said portions abutting the central portions of the disks.

2. A check wire for planters comprising a continuous length of wire provided with spaced check buttons including apertured disks having rounded peripheral portions and thin apertured central portions, said disks being rigidly located in position on the wire by radially upset portions of the wire, said upset portions abutting the central portions of the disks and lying substantially within planes tangent to the outer surfaces of the disks at right angles to the wire. 80

3. A check wire for planters comprising a continuous length of wire provided with spaced check buttons comprising disk shaped elements, the peripheral portions of which are substantially doughnut shaped and the central area of which is flat and comparatively thin, the wire passing through openings formed in the center of the disks and the buttons being rigidly located in position on the wire by upset portions of the wire of disk-like form, said portions abutting the central portions of the disk shaped elements. 90

4. A check wire for planters comprising a continuous length of wire provided with spaced check buttons comprising disk shaped elements the peripheral portions of which are substantially doughnut shaped and the central area of which is flat and comparatively thin, the wire passing through openings formed in the center of the disks and the buttons being rigidly located in position on the wire by upset portions of the wire of disk-like form, said portions abutting the central portions of the disk shaped elements and lying substantially within planes tangent to the outer surfaces of the disks at right angles to the wire. 100

5. A check wire for planters comprising a continuous length of wire provided with spaced check buttons comprising torus shaped elements formed with thin apertured central portions, said elements being rigidly located in position on the wire by radial upset portions of the wire, said portions abutting the central portions of the elements. 115

6. A check wire for planters comprising a continuous length of wire provided with spaced check buttons comprising disk shaped elements the peripheral portions of which are substantially torus shaped and the central area of which is flat and comparatively thin, said disks being rigidly located in position on the wire by upset portions of the wire of disk-like form, said portions abutting the central portions of the disks. 125

7. A check wire for planters comprising a continuous length of wire provided with check buttons comprising torus shaped elements forming the peripheral portions of the buttons, said elements being rigidly located in position on the wire and engaged by radially upset portions thereof. 135

8. A check wire for planters comprising a continuous length of wire provided with check buttons comprising torus shaped elements forming the peripheral portions of the buttons, said elements being rigidly located in position on the wire and engaged by radially upset portions thereof, said upset portions of the wire lying substantially within planes tangent to the outer surfaces of the torus shaped elements at right angles to the wire. 140
